ATTORNEY.

UNITED STATES PATENT OFFICE.

JEREMIAH R. KNAPP, OF NORWALK, OHIO.

TRUSS-PAD FRAME.

SPECIFICATION forming part of Letters Patent No. 623,375, dated April 18, 1899.

Application filed June 6, 1898. Serial No. 682,670. (No model.)

To all whom it may concern:

Be it known that I, JEREMIAH R. KNAPP, a citizen of the United States, residing at Norwalk, in the county of Huron and State of Ohio, have invented certain new and useful Improvements in Truss-Pad Frames; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to a truss-pad which may be formed of sheet-metal plates or other suitable material; and it consists in a slitted inner plate, a spring finger-like plate, and a curved outer plate, and so constructed that one or more portions of the slitted inner plate may be bent, as occasion requires, to work in conjunction with the free ends of the finger-like plate to engage the skin and draw together the loose folds thereof, whereby an easy and accommodating device may be had to control the rupture, all of which will be more fully described hereinafter.

In the accompanying drawings, Figure 1 is a perspective of a truss-pad which embodies my invention. Fig. 2 is a side elevation of the same.

1 represents the inner plate, which is preferably provided with four slits 2, thereby forming intermediate portions 3, which are adapted to be bent, and which plate is further provided at one end only thereof with a number of rivet-holes *a*. The spring 4, which may be of "line-of-beauty" form, is provided at each of its ends with rivet-holes *a*. The finger-like spring 5 has its inner end also provided with rivet-holes *a*, and its outer free end *x* is inwardly disposed. The curved spring 6 has rivet-holes *a* in one end thereof and an opening *c* in each end, which openings afford means for attachment to the truss-belt in the usual manner. The plate 1 and the springs 4, 5, and 6 are secured together in the order named by means of rivets *b*, passing through the rivet-holes *a*, the spring 4

having both of its ends fast, while the other springs just designated have each one fast and one free end. In practice, however, the plate 1 and the spring 5 only have one free end each, as both ends of the spring 6, as is evident, have to be attached to the belt of the truss.

It is evident that the pad may be formed by means of the plate and springs attached thereto, which will be adapted to effectually hold the rupture in place, the bendable portions 3 of the plate 1 working in conjunction with the free end *x* of the spring. The plate 1 bears against the body over the ruptured place, and the springs 4, 5, and 6 serve to exert a pressure upon the plate 1, which is regulated by the wearer by tightening or loosening the belt, to which the pad is attached in the well-known manner. All of these parts may be covered or not, as may be preferred. The plate 1 is given the desired shape by bending the portions 3 either outward or inward, according to the nature of the injury. By tightening or loosening the belt the springs 4, 5, and 6 exert a pressure upon the plate 1, which holds it in place.

This truss is intended to be used like all others. The plate 3 is applied over the ruptured place, and then any desired amount of pressure against the body is given to the plate 3 by the belt, which has its opposite ends connected in any suitable manner to the ends of the spring 6. The springs 4, 5, and 6 serve to exert a yielding pressure against the plate 3 and press it against the body with the desired degree of force.

Having thus described my invention, I claim—

1. In a truss-pad, a slitted inner plate having one fast and one free end, and provided with edges which are adapted to be turned inwardly or outwardly, combined with a flat curved spring which is secured at one end to one edge of the plate, and two flat curved springs which are rigidly connected to the outer end of the said curved spring, substantially as described.

2. In a truss-pad; an inner plate 1, which bears against the body, and having slits in its

edges, and bendable portions between said slits, the curved spring 4 secured at one end to one edge of the plate, and the two curved springs 5 and 6, secured rigidly to one end of the curved spring 4, and having their two free ends to curve outwardly in opposite directions, substantially as specified.

In testimony whereof I affix my signature in presence of two witnesses.

JEREMIAH R. KNAPP.
